[57] CLAIM

The ornamental design for a directional lighting system, as shown and described.

DESCRIPTION

FIG. 1 is a front perspective view of a directional lighting system showing my new design;

FIG. 2 is a side perspective view thereof.

The system is shaded to indicate contrast. The indicia and intersection are shown in broken lines for illustrative purposes only.

The panel on the third side of the system is identical to the panels shown in FIGS. 1 and 2. The interior sides of the panels are flat and plain.
